UNITED STATES PATENT OFFICE.

WILLIAM P. FEST, OF BROOKLYN, ASSIGNOR TO J. B. BREWSTER & COMPANY, OF NEW YORK, N. Y.

DESIGN FOR A CARRIAGE-BODY.

SPECIFICATION forming part of Design No. 19,951, dated June 24, 1890.

Application filed April 5, 1890. Serial No. 346,796. Term of patent 7 years.

To all whom it may concern:

Be it known that I, WILLIAM P. FEST, of Brooklyn, in the county of Kings and State of New York, have invented and produced a new and original Design for a Carriage-Body, of which the following is a specification, reference being had to the accompanying drawings, forming part thereof.

Figure 1 is a side view of a carriage containing my design. Fig. 2 is a front view thereof.

The leading feature of my design consists in the forward extension of the exterior surface of what is known among carriage-designers as the "coupé pillar," thereby making the general sweep of the carriage-sides in substantially continuous lines from rear to front of driver's seat, as shown.

The carriage shown in Fig. 1 will be narrower at the rear and in front than in the middle, producing a side sweep or curvature from *a* outward to about *b* and thence inward again to *c*. The portion of the side between the door and the broken line *x* *x* corresponds substantially in appearance with a coupé pillar, and the portion of the side forward of the line *x* *x* is a continuation substantially of the same surface lines or sweep to the forward end of the driver's seat.

What I claim is—

The design for carriage-bodies herein shown and described.

WILLIAM P. FEST.
